T. V. PLICE,
DOOR HANGER,
APPLICATION FILED FEB. 12, 1920.

1,341,584.

Patented May 25, 1920.

Thomas V. Inventor
By his Attorneys
Milwaukee & Keeley

UNITED STATES PATENT OFFICE.

THOMAS V. PLICE, OF ASHLAND, OHIO, ASSIGNOR TO THE TOPPING MANUFACTURING CO., OF ASHLAND, OHIO, A CORPORATION OF OHIO.

DOOR-HANGER.

1,341,584.

Specification of Letters Patent. Patented May 25, 1920.

Application filed February 12, 1920. Serial No. 358,036.

To all whom it may concern:

Be it known that I, THOMAS V. PLICE, a citizen of the United States of America, residing at Ashland, Ohio, have invented a new and useful improvement in Door-Hangers, of which the following is a specification.

My invention relates to devices known as door hangers, the object being to provide in 10 the hanger of the type adapted to doors which swing and slide, means for suspending the same from an overhead track and for mounting the same on the door in such a way that various adjustments can be effected. I 15 also provide improved means whereby the device may be readily reversed for application to either a right or a left hand door.

In the drawings:

Figure 1 is a front elevation of my invention on a very much reduced scale showing the method of application to a door.

Fig. 2 is a relatively enlarged view of the hanger.

Fig. 3 is an edge elevation of the hanger 25 shown in Fig. 2 looking from right to left.

Fig. 4 is a view similar to Fig. 3 showing the hanger with its mounting reversed.

Fig. 5 is a perspective view of a detail.

1 represents a track arranged to be secured to the main frame of a building above the door passage. 2—3 represent two doors. In this particular instance, the door 2 is hinged to the door casing so as to swing outward. The door 3 is hinged at its inner side 35 to the door 2 so that when the door 2 is swung open, the door 3 will fold back moving with the door 2. The free edge of the door 3 is suspended from the track 1 by means of a hanger, said hanger comprising 40 a frame 4 having a pulley 5 therein which rides on the track 1. 6 is a spindle which extends downwardly from the main frame 4 of the hanger. This spindle 6 is mounted to 45 swivel in a sleeve 7. The sleeve 7 is provided with an offset arm 8 which is mounted to slide in a socket 9, which socket is formed on or carried by a plate 10 which may be bolted to the door. The offset arm 8 is preferably round so that it may be turned in the 50 socket 9. In the opposite sides of the offset arm 8 are two grooves 8^a and 8^b. 11 is a set screw which passes through the side of the sleeve 9 so that the point of the screw may project into either one of the grooves 8^a or 8^b 55 so as to hold the offset arm 8 not only against

sliding but also against rotation. 12—12 are lock nuts on the spindle 6. The spindle 6 turns freely in the sleeve 7. In Fig. 2, I have shown the hanger as applied to a door which is designed to move to the left and 60 which may be termed a left hand door. In Fig. 4, I have shown the hanger as applied to what may be termed a right hand door. In adapting the said hanger to this door it requires merely the loosening up of the set 65 screw 11 so that the socket 9 and plate 10 may be rotated from the position indicated in Fig. 2 to the reverse position indicated in Fig. 4 in which position the parts may be again locked by the set screw 11. It frequently happens that the set back of the 70 door relatively to the track 1, or the offset of the latter relatively to the former, may vary considerably and heretofore brackets with varying degrees of offsets have been 75 provided to take care of the varying conditions, or in some instances, the hanger has been blocked off from the door by pieces of blocking. These methods however, are not only expensive but unsatisfactory. By my 80 improvement the offset of the hanger relatively to the face of the door may be varied by simply loosening the set screw 11 and sliding the offset arm 8 out to the desired degree, and then tightening up on the set 85 screw 11 to hold the parts fixedly in their newly adjusted position. It will be observed that these improvements constitute a very great convenience and will result in a substantial saving both to the manufacturer, 90 dealer and consumer, in that one single swivel hanger may be provided which is adjustable as to offset and reversible for right or left hand doors. The sleeve 7 with its offset arm 8 carried in the socket 9 having the base plate, 10 constitute a bracket, 95 which as above indicated is both adjustable and reversible.

In applying the device to the upper edge of a door, a hole should be bored in the door 100 to provide clearance for the inner end of the offset arm 8.

What I claim is:

1. A swivel door hanger comprising a frame for carrying an anti-friction roller, 105 a bracket comprising a sleeve in which the frame is swiveled and adjustable vertically, and a base having a socket and an offset arm carried by said sleeve and adjustable laterally, said arm being reversible in said 110

socket, with means for locking the said parts of the bracket together rigidly in various positions of adjustment.

2. A swivel door hanger comprising a frame for carrying an anti-friction roller, a bracket comprising a sleeve in which the frame is swiveled, and a base having a socket, an offset arm carried by said sleeve and adjustable and reversible longitudinally 10 in said socket, with means for locking the

said parts of the bracket together rigidly in various positions of adjustment, the opposite sides of said offset arm being recessed to form seats, and a device carried by the socket arranged to lock into either one of 15 said seats at will depending upon the position of the base plate relatively to said sleeve.

THOMAS V. PLICE.
